ABSTRACT OF THE DISCLOSURE

A geochemical exploration technique wherein petroleum source rocks are characterized on the basis of an "acid distribution ratio," i.e., the ratio of relative concentrations of even carbon number fatty acids to odd carbon number fatty acids found in rock samples. Preferably, the acid distribution ratio is determined with respect to fatty acids having more than sixteen carbon atoms and, more desirably, more than eighteen carbon atoms. Where a formation is found to exhibit an acid distribution ratio of 1.3 or less it is indicated as a possible petroleum source rock and a well may be drilled into a reservoir rock formation in fluid communication with the source rock formation.

This invention relates to geochemical exploration for petroleum minerals, and more particularly to a geochemical exploration method which involves the identification of petroleum source rock formations.

Petroleum is found in commercial quantities in sub-surface rock formations such as sandstones and limestones. The presence of a petroleum deposit in a subterranean formation is not ordinarily manifested by readily discernible indicia at the earth's surface. Accordingly, various techniques have been evolved in exploring for oil. Among these are those which fall within the general classification of geochemical exploration.

In most geochemical exploration techniques, a search is made, usually at or near the surface of the earth, for components of petroleum, precursors of petroleum, or derivatives thereof. These procedures are based upon the theory that these materials may have migrated to or near the surface of the earth from an underlying petroleum reservoir. Thus, where materials such as hydrocarbons which are normally constituent components of petroleum are found, the presence of a subterranean reservoir of petroleum in the area is indicated.

While these techniques are extremely valuable in determining the presence of petroleum within a general area, they usually give little indication of the location of the underlying petroleum reservoir. Other exploration procedures such as seismic surveying may be utilized to identify possible petroleum reservoirs at subterranean locations in the earth's crust. However, while such measures may give valuable information as to subterranean structures favorable to the accumulation of petroleum, they leave much to be desired in regard to determining which, if any, of such structures actually contain petroleum deposits.

In attempting to ascertain whether such structures contain petroleum, geologists have in recent years turned to exploration techniques based upon the so-called "source rock" concept. Under this concept, it is assumed that petroleum hydrocarbons are formed during long periods of burial in fine grained sediments of high organic matter content, the petroleum hydrocarbons being derived from organic matter of biologic origin which was deposited with these sediments in a marine environment. The exact mechanism by which oil is formed within such sediments, i.e., source rocks, is not known with certainty. After the oil-forming mechanism has taken place, it is thought that the petroleum hydrocarbons in the source rock then

2

migrated to more permeable reservoir rocks where they accumulated in the concentrated deposits found today.

One important series of compounds found in petroleum oils are the normal paraffins. Most crude oils contain approximately equal concentrations of odd and even carbon number paraffins with the ratio of odd to even usually falling within the range of about 0.9 to 1.15. On the other hand, most sediments of relatively recent origin exhibit a relatively high ratio of odd carbon number paraffin concentrations to even carbon number paraffin concentrations.

While, as noted above, the nature of the oil-forming mechanism within source rocks is open to question, it has been postulated that many of the normal paraffins found in petroleum oils are derived from relatively high molecular weight fatty acids contained in the biologic material originally deposited in the source rock sediment. In current biological systems, fatty acids having an even number of carbon atoms vastly predominate over those having an odd number of carbon atoms. With the assumption that this same general relationship existed for the biologic material precursive of petroleum, it has been postulated that in the formation of petroleum the fatty acids undergo a transformation reaction in which are formed alkyl radicals that in turn react to form fatty acids and normal paraffins having one less carbon atom than their fatty acid precursors. That is, fatty acids having N carbon atoms would produce fatty acids and normal paraffins each having N-1 carbon atoms. This reaction progresses until most of the fatty acids originally present in the deposited biologic material have been reduced to fatty acids and normal paraffins of lower molecular weights with the distribution between even and odd carbon number paraffins being about equal. For a detailed description of a theory of petroleum formation in which the transformation process is postulated to involve decarboxylation of fatty acids, reference is made to Cooper, J. E. et al., "A Postulated Role of Fatty Acids in Petroleum Formation," *Geochimica et Cosmochimica Acta*, 1963, vol. 27, pp. 1113-1127.

In accordance with the above concepts of petroleum formation and accumulation, it has been proposed to locate petroleum source rocks on the basis of their normal paraffin content in exploring for petroleum reservoirs. More particularly, it has been proposed to identify petroleum source rocks by the distribution of normal paraffins therein, with a rock having a ratio of odd to even carbon number paraffin concentrations near 1.0, i.e., on the order of the ratio found in most petroleum crude oils, being indicated as a source rock. A detailed description of this exploration technique and certain investigations relative thereto may be found in Bray, E. E. et al., "Distribution of N-Paraffins as a Clue to Recognition of Source Beds," *Geochimica et Cosmochimica Acta*, 1961, vol. 22, pp. 2-15.

While this technique has not as yet had extensive practical application, it is possible that experience may prove it to be a valuable tool in exploring for oil. However, several difficulties are involved in attempts to identify source rocks on the basis of their normal paraffin content. One potential source of error stems from the possibility that the source rock has undergone an efficient loss of normal paraffins to the reservoir rock during the oil accumulation process. Thus, though the sediment is in fact a source rock, the concentration of normal paraffins remaining therein may be exceedingly low and their distribution difficult, if not impossible, to determine by known analytical methods. Also, in some instances, hypothesized source rocks do not occur as outcroppings, thus necessitating the drilling of a well into subterranean location of the source rock in order to obtain samples. Common drilling procedures often involve the use of oil

as a component in the drilling mud. Normal paraffins contained in such oil may contaminate the samples, thus rendering an accurate analysis of the samples impossible. Also, oil naturally produced in the well, e.g., due to the well in the course of drilling penetrating an unknown reservoir rock containing petroleum hydrocarbons, is a possible source of sample contamination.

In accordance with the instant invention, there is provided a new and improved geochemical exploration method involving the identification of petroleum source rock sediments on the basis of a distribution of even and odd carbon number fatty acids contained therein, and more particularly the distribution of such acids above a specified molecular weight. By the term "fatty acids," as used herein and in the appended claims, is meant straight-chain saturated acids of the following general formula:

As noted above, a petroleum source rock may have undergone an efficient loss of normal paraffins to a reservoir rock during the oil accumulation process, thus rendering it difficult, if not impossible, to characterize the rock sediment as a source rock on the basis of its normal paraffin distributions. However, the migration of fatty acids from the source rock to the reservoir rock during the oil accumulation period may have been less efficient than that of the normal paraffins. Thus, a source rock having very low normal paraffin concentrations may contain fatty acids whose presence and distribution may be determined analytically. Also, although the source rock may contain normal paraffins in discernible concentrations, the paraffin content of the rock is subject to contamination as in drilling operations as noted above. Oils added to drilling fluids or naturally produced in an exploratory well may contain fatty acids, but the concentration usually will be so low that any possible contamination of the rock would be slight and below the measurable range.

While the possibility of contamination of source rocks with regard to their fatty acid content is less than the possibility of contamination with regard to their normal paraffin content, such contamination is conceivable and even probable under some circumstances. A possible source of fatty acid contamination is by deposition of modern biologic material. The most common fatty acids found in natural materials have 12, 14, 16, and 18 carbon atoms with those of 16 carbon atoms being the most prominent. Therefore, in accordance with one aspect of the invention, those acids having 16 or less carbon atoms, and preferably those acids having 18 or less carbon atoms, are excluded in the characterization of source rocks on the basis of their distribution of even and odd carbon number fatty acids.

For a better understanding of the present invention and the objects achieved thereby, reference may be had to the following detailed description.

In carrying out the present invention, rock samples taken from the earth's crust are analyzed with regard to their fatty acid content to determine for each sample the ratio between the sum of relative concentrations of even carbon number fatty acids and the sum of relative concentrations of odd carbon number fatty acids. The ratios for the samples then are correlated with each other and the locations in the earth's crust from which the samples were taken to determine, in accordance with certain criteria as explained hereinafter, possible source rocks of petroleum hydrocarbons. Thereafter, further exploratory procedures may be undertaken as described below to locate reservoir rocks to which petroleum hydrocarbons have migrated from the designated source rocks.

Since, as noted previously, even carbon number fatty acids are present in relatively ample amounts in natural biologic products of either plant or animal origin while fatty acids having an odd number of carbon atoms are present only in trace amounts, it has been assumed that

in a sediment when it was originally deposited the ratio of even to odd carbon number fatty acids was relatively high. This assumption is consistent with observations that have shown even carbon number fatty acids to be much more abundant in modern sediments than odd carbon number fatty acids.

It also has been observed that in certain ancient sedimentary rocks the ratio of even to odd carbon number fatty acid concentrations is less than the ratio generally found in relatively modern sediments. It is my belief that this decreased ratio of even to odd carbon number fatty acid concentrations, hereinafter referred to as the "acid distribution ratio," in old sedimentary rocks reflects the increasing degree of degradation of fatty acids as they undergo the transformation process referred to above in the formation of normal paraffins. It is therefore proposed that the ratio of relative concentrations of even and odd carbon number fatty acids found in a particular rock is an indication of the likelihood of this rock being a source rock; and that of a plurality of rock formations within a geographical area and/or a geological time zone the formation having the lowest even to odd carbon number fatty acid ratio is the most likely to be a petroleum source rock. More particularly, it is my hypothesis that the formation of the normal paraffins of relatively high molecular weight commonly found in crude oils is accompanied by a degradation of the normal fatty acids in the precursory materials to such an extent that the ratio of even to odd carbon number fatty acid concentrations is not greater than 1.3 and in most cases not greater than 1.2.

As a first step in practicing the instant invention, one or more samples from the rock or rocks under investigation are obtained and analyzed for their relative fatty acid concentrations in order to determine the ratio between even carbon number fatty acids and odd carbon number fatty acids in the rock or rocks. An analysis of such samples for their fatty acid content may be carried out by any suitable procedure. However, care must be taken to employ a procedure which will yield accurate results since the fatty acid concentration in such rocks normally will be relatively low.

In a preferred procedure for analyzing for fatty acids the rock sample is dried and crushed to obtain a homogeneous mixture. The acids then are extracted in the form of their salts from the rock. This may be accomplished by adding a suitable amount of pulverized rock sample, e.g., about 500 grams, to an amount within the range of about 500 to 1300 milliliters of a solution of about 10 percent by weight potassium hydroxide and 90 percent by weight methanol. During the addition of the pulverized rock sample, the mixture is constantly stirred. The sample then is refluxed at a temperature of about 60° C. with stirring for about eight hours, after which the extracted solution is recovered by centrifuging from the mixture. The resulting solution is thereafter concentrated by distillation. For example, the solution can be concentrated to a volume of about 400 milliliters by distillation in a two-foot Vigreux column.

The concentrated extract then is acidified in order to form the fatty acids. This may be accomplished by adding to about 200 milliliters of the extract about 500 milliliters of distilled water and sufficient hydrochloric acid to make the resulting solution have a pH of about one or less. The concentrate then is extracted with carbon tetrachloride to remove and recover the fatty acids. This may be done by adding the mixture to a separatory funnel, then extracting it successively with 50 milliliters, 30 milliliters, and 20 milliliters of carbon tetrachloride. This extract then is concentrated by distillation to a volume of about 10 to 15 milliliters. The concentrate then is transferred to a suitable vial and the remaining solvent is removed by employing a stream of filtered air at a temperature of about 40° C.

Following removal of the solvent, the acids are treated to form the methyl esters thereof. To the residue following removal of the solvent are added 0.5 milliliter of benzene and 3.5 milliliters of a solution of about 10 percent by weight boron trifluoride and 90 percent by weight methanol. This mixture then is heated in a steam bath for a period of about five minutes and then cooled. Thereafter, one milliliter of benzene and two milliliters of distilled water are added to the solution and the resulting mixture is shaken and centrifuged. The benzene layer containing the methyl esters then is recovered.

Following the esterification procedure, a urea adduct of the methyl esters is prepared. This is accomplished by adding three milliliters of methanol saturated with urea to the benzene solution. The mixture is agitated and thereafter cooled to a temperature of about 0° C. and maintained at this temperature for a period of about 18 hours. The urea adduct of the methyl esters appears in the form of crystals. The urea adduct crystals are separated from the liquid by centrifuging and the crystals thereafter are washed with benzene. This may be accomplished by washing the crystals twice, utilizing one milliliter portion of benzene each time. The resulting urea adduct then is decomposed in about two milliliters of water. The resulting solution is shaken and centrifuged and the benzene layer recovered.

The benzene layer thus recovered normally will contain, in addition to the methyl esters of the fatty acids, normal paraffins which were originally present in the rock sample. Such normal paraffins may be removed by silica gel chromatography. In this phase of the analysis technique, the benzene solvent in the recovered solution is removed by evaporation at 40° C. under a filtered air stream. The remaining extract is dissolved in a suitable amount, e.g., five milliliters, of normal heptane and the resulting solution is added to a nine-milliliter diameter glass chromatographic column packed with suitable silica gel. For example, the column may be packed with nine grams of 100 to 200 mesh activated silica gel and pre-wet with five milliliters of normal heptane. The column then is eluted successively with three five-milliliter portions of normal heptane, one five-milliliter portion of benzene, and three five-milliliter portions of methanol. The methyl esters of the fatty acids are recovered in the benzene-methanol fraction collected from the chromatographic column.

In many cases it will be desirable at this stage of the analysis procedure to confirm the presence of these methyl esters in the benzene-methanol fraction. This may be accomplished by infrared spectrometry. In this case, the benzene and methanol solvents may be removed by evaporation at 40° C. under air. The remaining extract is dissolved in a suitable amount, e.g., about three milliliters of carbon disulfide. The resulting carbon disulfide solution then may be analyzed in an infrared spectrophotometer suitable for scanning the two- to fifteen-micron region in order to verify the presence of methyl esters of the fatty acids in the benzene-methanol fraction.

Following the infrared spectrometry, the carbon disulfide solvent is removed by evaporation at 40° C. under air and the remaining extract is dissolved in benzene. The resulting benzene solution of methyl esters then is analyzed by gas chromatography in order to determine the relative concentrations of methyl esters of fatty acids contained therein. Any suitable chromatographic analysis apparatus may be employed for this purpose. In experimental work an F&M Model 500 gas chromatograph having a 24-inch by 1/4-inch column packed with about four percent silicone gum rubber on 60 to 80 mesh silanized diatomite aggregates available under the trade name "Chromosorb W" has proved to be satisfactory.

In carrying out the analysis, helium may be utilized as the carrier gas and the column temperature may be increased from an initial temperature of about 100° C. to a maximum of about 350° C. at the rate of about 5.6°

C. per minute. Thereafter, the temperature may be held at 350° C. until the esters are eluted completely.

5 The chromatographic column may be calibrated with a standard solution of methyl esters of fatty acids in order to determine the elution times of the esters of the various acids under investigation. In experimental procedures involving this analysis technique, a gas chromatograph of the above type was calibrated with a standard solution containing methyl esters of normal fatty acids having 18 and 26 carbon atoms per molecule. Retention times and instrument sensitivities for other methyl esters of normal fatty acids were obtained by interpolation and extrapolation of the calibration curves.

15 The chromatogram produced by the chromatographic analysis will indicate the concentrations of methyl esters and therefore the relative concentrations of their parent fatty acids in the sample. Each ester appears on the chromatogram as a peak at a definite recording time. The area under each peak is proportional to the concentration of acid in the sample. The relative concentrations of the even and odd carbon number fatty acids analyzed may thus be determined from the gas chromatogram.

20 The above-described analytical procedure should not be considered to be determinative with regard to the absolute concentrations of the various acids in a sample. The procedure may not, and probably in most cases does not, recover all of the fatty acid content of the sample. However, it is considered to give extremely accurate results with regard to the relative concentrations of the respective fatty acids in the sample.

25 Certain factors should be considered in characterizing rocks on the basis of their fatty acid distributions. In order to avoid possible erroneous results due to contamination, the ratio between even and odd carbon number fatty acid concentrations should be determined only with regard to acids having more than 16 carbon atoms and preferably more than 18 carbon atoms. On the other hand, source rocks contain only small amounts of fatty acids with 34 or more carbon atoms and their inclusion in determining the acid distribution ratio should have little effect thereon. Also, the relative concentrations of such acids found in source rocks are difficult to measure with a high degree of accuracy and their inclusion in determining the acid distribution ratio would more likely lead to error rather than strengthening the results. Thus, it usually will be desirable to exclude these high molecular weight acids and it is preferred in carrying out the present invention to determine the acid distribution ratio on the basis of relative concentrations of fatty acids having more than 18 carbon atoms and less than 34 carbon atoms.

30 The acid distribution ratio may be determined for a sample simply by dividing the sum of the relative concentrations of the even carbon number fatty acids by the sum of the relative concentrations of the odd carbon number fatty acids. In order to avoid a distortion of the ratio, it should be determined with regard to the same number of each of the two classes of acids. Also, the two classes of acids should be as close as possible with regard to their molecular weights. For example, if the cumulative relative concentration for even carbon number acids is determined on the basis of each even acid within the range of C₂₀ through C₃₂, this value for the odd carbon number acids should be determined on the basis of each odd acid within the range of C₁₉ through C₃₁ or C₂₁ through C₃₃. If for any reason there is a departure from the above standards for a particular sample, this same departure should be observed for all samples correlated therewith in order to achieve comparative uniformity.

35 The ratio may be determined by other statistically accepted techniques. For example, it may be determined by taking the mean of two ratios determined on the basis of even carbon number acid concentrations over a common molecular weight range and odd carbon number acid concentrations over the two molecular weight ranges

most proximate to the common range. The acid distribution ratio (ADR) determined by this technique may be defined by the following equation:

ADR =

$$\frac{1}{2} \left(\frac{\sum \text{even acid concentrations } C_N \text{ thru } C_{N+M}}{\sum \text{odd acid concentrations } C_{N-1} \text{ thru } C_{N+M-1}} + \frac{\sum \text{even acid concentrations } C_N \text{ thru } C_{N+M}}{\sum \text{odd acid concentrations } C_{N+1} \text{ thru } C_{N+M+1}} \right) \quad (1)$$

wherein N and M are even integers. For the preferred range given above, Equation 1 becomes:

ADR =

$$\frac{1}{2} \left(\frac{\sum \text{even acid concentrations } C_{20} \text{ thru } C_{32}}{\sum \text{odd acid concentrations } C_{19} \text{ thru } C_{31}} + \frac{\sum \text{even acid concentrations } C_{20} \text{ thru } C_{32}}{\sum \text{odd acid concentrations } C_{21} \text{ thru } C_{33}} \right) \quad (2)$$

The acid distribution ratio preferably is determined by the technique of Equation 1 since it reduces the effect of unusually large or small concentrations of odd carbon number fatty acids at the ends of the summation ranges. The acid distribution ratio as determined by this technique thus provides an indication of the distribution of fatty acids as it exists over a relatively broad molecular weight range.

A number of various procedures may be followed in practicing the instant invention. For example, the invention may be utilized as a primary exploratory technique in order to determine the possibility of petroleum accumulations within a general geographical area of the earth's surface. In this case, it usually will be preferable to obtain samples from a large number of locations in the earth's crust. The samples may be obtained either at the surface of the earth or by drilling to subsurface locations in the earth's crust. If surface samples are taken, it usually will be desired to obtain samples from a depth of at least a few feet in order to reduce possible anomalous effects introduced by weathering or surface contamination. Also, the sampling stations may be chosen at random or on the basis of a predetermined scheme. For example, in surface surveying, sampling stations may be located at intervals of about 5 to 40 feet on surface outcrops of suitable lithologic units.

The samples thus collected are analyzed by the above-described or other suitable analytical procedure to obtain for each sample the ratio between the sum of relative concentrations of a plurality of even carbon number fatty acids and the sum of relative concentrations of a plurality of odd carbon number fatty acids. The ratios for the respective samples then are correlated with each other and the locations at the earth's surface at which the samples were taken in order to ascertain possible source rocks of petroleum hydrocarbons in the areas. This may be accomplished by plotting the acid distribution ratio for each sample at its respective location on a geographical map of the area surveyed. If the results of this survey indicate that certain sediment within the earth's crusts in the area under investigation may be source rocks, further exploratory measures may then be carried out.

The instant invention also may be utilized as a supplementary exploratory tool in areas in which other prospecting operations have already been carried out. For example, seismic surveying of a particular locality may indicate the presence of subsurface sedimentary structures within which petroleum hydrocarbons may be accumulated. In this case, the instant invention can provide a valuable tool in determining which one of a plurality of surface structures favorable to the accumulation of hydrocarbons may actually contain petroleum deposits.

In this use of the invention, at least one and preferably a plurality of rock samples may be obtained from each of the rock formations which may be possible petroleum source rocks. The possible source rock formations usually will be fine grained sediments such as shales, although in some cases carbonate rocks such as limestones and dolomites may be considered as possible source rocks. These samples then are analyzed to determine the ratio between the sum of relative concentrations of even carbon number fatty acids and odd carbon number fatty acids. These ratios then are correlated with each other and the rock formations from which the samples were obtained to ascertain the rock formation having the lowest acid distribution ratio. This rock formation is considered the most likely to have been a source rock from which petroleum hydrocarbons may have migrated. The location of this rock formation in the earth's crust then may be correlated with respect to the locations of the aforementioned possible reservoir rocks and a well is drilled into a reservoir rock formation which is in fluid communication with the designated source rock formation and has a permeability greater than the source rock formation. Preferably, the well is drilled into a reservoir formation which is in a contiguous relationship with the source rock formation, that is, one that lies next to the source rock and thus provides a ready acceptor for petroleum formed within the source rock and migrating therefrom. However, in some cases, it may be desirable to drill a well into a promising rock formation which is not in contiguous relationship with the source rock, but is in fluid communication therewith by other means such as through subterranean faults or joints.

In most cases it will be preferred to designate as source rocks only those rock formations having a ratio of even to odd carbon number fatty acid concentrations, preferably as determined in accordance with Equation 1, of about 1.3 or lower, and preferably about 1.2 or lower. In this regard, surveys of rock formations identified as source rocks by techniques independent of the present invention have shown that such formations almost universally display an acid distribution ratio of not more than 1.3, and in most cases the acid distribution ratio has been 1.2 or less.

Only very rarely has a formation otherwise identified as a source rock been found to have an acid distribution ratio of more than 1.3. Notwithstanding this, it may be advisable, under certain circumstances, to consider rock formations having higher such ratios as possible source rocks. For example, other exploration techniques such as soil-gas analysis, etc., carried out in an area may be strongly indicative of the propinquity of subsurface petroleum accumulations. However, an exploratory survey in accordance with the instant invention may fail to reveal source-rock type sediments having fatty acid distributions within the aforementioned ranges. In this case, in view of the strong independent evidence of petroleum accumulations, it may be desirable to consider the rock having the lowest acid distribution ratio as a petroleum source rock even though the ratio of even to odd carbon number fatty acid concentrations may be greater than 1.3, e.g., on the order of 1.6. Thus, in this situation, an exploratory well would be drilled into a subsurface rock formation which has suitable reservoir characteristics and is in fluid communication with the designated source rock. As before, the rock formation into which the well is drilled preferably will be in a contiguous relationship with the source rock. However, fluid communication between the formations may be established by other means such as through faulting.

Having described specific embodiments of the instant invention, it will be understood that further modifications thereof may be suggested to those skilled in the art, and it is intended to cover all such modifications as fall within the scope of the appended claims.

What is claimed is:

1. In a method of geochemical exploration, the steps comprising:
  - obtaining rock samples from a plurality of locations in the earth's crust,
  - analyzing said samples for fatty acids to determine for each of said samples the ratio between the sum of relative concentrations of a plurality of even carbon number fatty acids contained therein having more than 16 carbon atoms and the sum of relative concentrations of a plurality of odd carbon number fatty acids contained therein having more than 16 carbon atoms, and
  - correlating said ratios with each other and the locations in the earth's crust of their respective samples to ascertain source rocks of petroleum hydrocarbons.
2. The method of claim 1 wherein each of said fatty acids has more than 18 carbon atoms.
3. The method of claim 1 wherein each of said fatty acids has more than 18 carbon atoms and less than 34 carbon atoms.
4. In a method of geochemical exploration, the steps comprising:
  - obtaining at least one sample from each of a plurality of rock formations in the earth's crust,
  - analyzing said samples for fatty acids to determine for each of said formations the ratio between the sum of relative concentrations of a plurality of even carbon number fatty acids contained therein and the sum of relative concentrations of a plurality of odd carbon number fatty acids contained therein,
  - correlating said ratios with each other and said rock formations to ascertain the one of said rock formations having the lowest ratio of even carbon number fatty acid concentrations to odd carbon number fatty acid concentrations of said plurality of rock formations, and
  - drilling a well into a subsurface reservoir rock formation in fluid communication with said one of said rock formations, said reservoir rock formation having a permeability greater than said one of said rock formations.
5. The method of claim 4 wherein each of said fatty acids has more than 16 carbon atoms.
6. The method of claim 4 wherein each of said fatty acids has more than 18 carbon atoms and less than 34 carbon atoms.

7. The method of claim 4 wherein each of said fatty acids has more than 18 carbon atoms.
8. The method of claim 7 wherein at least a portion of said reservoir rock formation is in a contiguous relationship with at least a portion of said one of said rock formations.
9. In a method of geochemical exploration, the steps comprising:
  - obtaining at least one sample from a rock formation in the earth's crust,
  - analyzing said sample to determine the ratio between the sum of relative concentrations of a plurality of even carbon number fatty acids contained therein and the sum of relative concentrations of a plurality of odd carbon number fatty acids contained therein, and
  - where the ratio of even carbon number fatty acid concentration to odd carbon number fatty acid concentration is not greater than 1.3, indicating said formation to be a source rock of petroleum hydrocarbons, drilling a well into a subsurface reservoir rock formation in fluid communication with said source rock formation, said reservoir rock formation having a permeability greater than said source rock formation.
10. The method of claim 9 wherein said ratio of even carbon number fatty acid concentration to odd carbon number fatty acid concentration is not greater than 1.2.
11. The method of claim 9 wherein each of said fatty acids has more than 16 carbon atoms.
12. The method of claim 9 wherein each of said fatty acids has more than 18 carbon atoms and less than 34 carbon atoms.
13. The method of claim 9 wherein each of said fatty acids has more than 18 carbon atoms.
14. The method of claim 13 wherein at least a portion of said reservoir rock formation is in a contiguous relationship with at least a portion of said source rock formation.
